(57) **CLAIM**

The ornamental design for a hat brim as shown and described.

DESCRIPTION

FIG. 1 is a front perspective view of a hat brim showing our new design;

FIG. 2 is a bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 is a front perspective view of the hat brim in a condition of use.

The broken lines depict portions of the hat brim that form no part of the claimed design. The broken lines illustrating a hat crown and a figurine accessory mounted to the hat brim in FIG. 9 are for illustrating the hat brim in a condition of use and form no part of the claimed design.

1 Claim, 9 Drawing Sheets
